UNITED STATES PATENT OFFICE.

SAMUEL G. BROWN, OF LYNN, MASSACHUSETTS.

DRAIN-TRAP.

1,082,730.

Specification of Letters Patent. Patented Dec. 30, 1913.

Application filed August 23, 1912. Serial No. 716,608.

To all whom it may concern:

Be it known that I, SAMUEL G. BROWN, a citizen of the United States, residing at Lynn, in the county of Essex and State of Massachusetts, have invented certain new and useful Improvements in Drain-Traps; and I do hereby declare the following to be a full, clear, and exact description of the invention, such as will enable others skilled in the art to which it appertains to make and use the same.

The present invention relates to an improvement in drain traps and more particularly drain traps for automobile wash stands and the like. Automobiles on the wash stand drip water, sand, oil and gasoline, and it is desirable that the gasoline, oil and sand should not be permitted to flow into the sewer, so in some instances it has been proposed to use an elaborate apparatus for separating the oil from the water, and no attention, so far, has been given to preventing sand from flowing directly into the sewer.

The object of the present invention is to produce a simple and inexpensive drain trap which will separate the water, sand, oil and gasoline, and permit only the water to flow into the sewer.

To the above end, the present invention consists in the trap hereinafter described and particularly defined in the claims.

In the accompanying drawings illustrating the preferred form of the invention, Figure 1 is a sectional elevation taken on the line 1—1 of Fig. 4; Fig. 2 is a sectional elevation on the line 2—2 of Fig. 4; Fig. 3 is a partial sectional elevation on the line 3—3 of Fig. 4; and Fig. 4 is a plan of the trap with the floor plate removed.

The trap comprises a main body 10 having an oil well body 11 integral therewith located at one side thereof for receiving the oil bucket or pail 12. The upper edge of the main body 10 and the oil well body 11 is provided with a flange 13 extending completely around the body and adapted to be interlocked with the concrete floor of the wash stand.

The trap is covered with a floor plate 14 provided with a number of holes 15 in the depression 16 for the entrance of the drippings from the machine, to wit, water, sand, oil and gasoline. The floor plate 14 is removable, being loosely received in the top of the main body 10. The water, sand, oil

and gasoline flowing into the trap through the holes in the floor plate 14 are received in the baffle basin 17 having a floor 18 which is inclined toward a central opening 19 therein, through which such materials are discharged into the oil separator 20. The hole 19 is surrounded by a depending flange 21 forming a discharge pipe extending down into the oil separator 20. The baffle basin 17 is supported in the main body of the trap upon the shoulder 22 thereof. This oil separator 20 is supported from the lower side of the baffle basin 17 and extends down into the sand bucket 23. The sand bucket is open at its top and the water flows down through the oil separator 20 out through the opening 24 at the bottom thereof into the sand bucket and thence rises and flows over the lip of the sand bucket and falls into the trap body 10.

At the bottom of the trap body the water outlet 25 is provided which discharges through the sewer pipe 26, such sewer pipe running upward a ways before it discharges into the sewer proper to maintain a constant seal in the sewer pipe so as to prevent any flow of gases from the sewer pipe into the trap. The oil which falls into the oil separator remains floating on the water contained therein and gradually accumulates until it rises to the level of the mouth of the oil spout 27. The amount of oil, therefore, in the oil separator when the oil is flowing away therefrom, extends from the level 28 to the level 29, the former level being the level of the mouth of the oil spout and the latter level being the level of the water upon which the oil floats in the oil separator. The mouth of the oil spout is flat and level and the oil flows off of the top of the body of oil in the oil separator 20 through the oil chute 27 and is discharged into the oil bucket or pail 12. It is to be understood, of course, that at this time the water in the sand bucket 23 is overflowing the lip of the bucket and therefore has a level 30 on the outside of the oil separator 20, the difference in specific gravity of the oil and the water causing the oil to float at a higher level inside of the oil separator from that at which the water is maintained on the outside thereof. In this way, it will be seen that the mixed oil and water flowing into the oil separator is separated there, the small globules of oil having time to coalesce and to unite into a solid body of oil before

it reaches the level of the mouth of the oil chute 27, and that the water which enters the oil separator flows down through the bottom of the oil separator into the sand 5 bucket. No sand remains in the oil separator 20 as it flows out into the sand bucket with the water, but here the sand is caught in the sand bucket while the water flows on over the top of the sand bucket and falls into the 10 trap body. The gasoline which enters the oil separator with the oil, water and sand, is removed from the trap by a process of evaporation.

The trap body is provided at opposite 15 sides, as seen in Fig. 3, with air pipe connections 31 and 32. These air openings register with holes 33 and 34 formed in the baffle basin 17 underneath the inclined floor 18 thereof. One of the air openings 31, for 20 example, will be connected with an air inlet drawn from any convenient location, and the other air opening 32 will be piped through the building for a distance and discharged at a higher level than the entrance of the air 25 through the opening 31, so that a current of air will be induced to flow through the trap body entering through the hole 33 and discharging through the hole 34, thereby operating to evaporate any gasoline which may 30 be present in the oil separator. The lower end of the pipe 21 depending from the floor 18 of the baffle basin dips below the surface of the oil contained in the oil separator 20, and some gasoline may remain in this pipe 35 21, but the exposed surface of such gasoline is small, and any gasoline vaporized therefrom is of such insignificant amount as to be entirely without any danger. Of course, the oil, water and gasoline flowing down through 40 the hole 19 is more or less mixed together, and it has been found that a large part of the gasoline contained is carried by the mixture down below the lower end of the pipe 21, so that it is discharged into the oil separator 20 and rises to the surface of the oil 45 standing around the pipe 21. The oil well 11 is covered with a screw cap 35 to prevent the escape of any gasoline vapors from the trap.

50 The sand bucket 23 is so supported that when the weight of the sand contained therein amounts to a certain predetermined quantity, requiring it to be emptied, the bucket will operate to close the opening in the lower 55 end of the pipe 21, thereby causing the further ingress of water into the trap to be stopped and causing the trap to overflow on the floor of the wash stand. This is the signal by which the trap indicates that it is 60 in condition requiring the emptying of the sand bucket. Of course, the floor plate 14 is not fitted tightly in the flange 13 in the trap body, but in the use of the apparatus the sand and materials flowing into the 65 crevice between the floor plate and the flange

13 of the trap body is such as to make a closure that is practically tight, for the purposes of preventing water from entering in any substantial amounts, and thereby causing the water to rise up on to the floor of the 70 wash stand.

The arrangement for supporting the sand bucket in such manner as to cause it to close the lower end of the pipe 21 is as follows: The sand bucket 23 is provided with ears 36 75 to which are pivotally attached links 37 slotted at 38 to receive the ends of the levers 39 pivoted at 40 on the fulcrums 41. To the upper ends of the links 37 are attached the rings 42. The inner ends 43 of the levers 39 engage the under side of the head 44 secured to the upper end of the sleeve 45 which supports upon its lower end the counter-weight 46. The above described arrangement is such that when an amount of sand collects 80 in the sand bucket 23 sufficient to overbalance the weight 46, thereupon the weight is lifted and the upper surface of the weight, acting as a valve, closes the mouth of the pipe 21 and prevents the further ingress of 85 material into the trap, causing it to flood, as above described. Thereupon the floor plate 14 is removed, and by taking hold of the rings 42 the links 37 are transferred from the ends of the levers 39 to the hooks 47 90 projecting inwardly from the side walls of the body of the trap, thus supporting the sand bucket on these hooks 47. Then the T head 48 mounted upon the upper end of the rod 49 which passes vertically through 95 the sleeve 45 and carries at its lower end the valve 50 is pulled upward, thereby lifting the valve 50 and drawing it into the mouth of the oil separator, thereby closing the mouth of such separator, and by further lifting upon the handle the baffle basin and oil separator are lifted entirely out of the trap body, maintaining the oil and water in the oil separator by the pressure of the valve 50 100 against the mouth in the lower end of the oil separator 20. These parts may then be stood upon the floor, the pressure of the weight of the parts upon the valve 50 holding such valve closed. Then the sand bucket may be 105 lifted out of the trap body and emptied of its accumulated sand. At the same time, the closure 35 will be taken out and the oil bucket 12 will be lifted out and emptied, returned to the oil well, the closure 35 again put in place, after which the sand bucket 23, 110 having been returned to the trap 20, the baffle basin and oil separator will be returned to their positions in the trap body, lifting it up by the handle 48 as before, and dropping it down into the trap body. Then the straps 115 37 will be transferred from the hooks 47 to the ends of the levers 39, the floor plate 14 will be returned to its place and the trap will be ready for further use. It is to be observed in this connection that the water un- 120 125 130

derneath the oil in the oil separator flows out into the sand bucket when the baffle basin and oil separator are returned to the trap body and that the water is sufficient in quantity to cover the mouth 24 of the oil separator so that no oil enters the sand bucket.

The outer ends of the lever 39 project through the walls 51 of the reëntrant chambers formed in the side walls of the baffle basin (see Fig. 4 for plan, Fig. 2 for section, and Fig. 3 for elevation showing these reëntrant chambers). The upper surface of this wall 51 engages the under side of the floor plate 14 so as to prevent water from overflowing the walls 15 and thereby continuing to permit the escape of water from the trap, although it shall have reached a condition requiring its being emptied.

The operation of the trap has been set forth in connection with the description of the various parts during their description, but it may perhaps be convenient, to recapitulate here, observing that the trap is so constructed that when an accumulation of a certain amount of sand has taken place, the sand bucket becomes so heavy that it overbalances the counter-weight and closes the entrance opening, preventing the further ingress of material to the trap, thereupon the trap, in continued use, will overflow on the floor of the wash stand and indicates that the sand bucket should be emptied. Furthermore, that any gasoline which is carried into the trap with the water, oil and sand, will be evaporated and carried out of doors, where it will be dissipated without danger. Again, that when it is desired to empty the trap, only the simplest operations are required of taking up the floor plate, transferring the sand bucket support from the counter-weight levers to the stationary hooks and, thereupon lifting out all of the unseparated oil without permitting it to be spilled into the sewer or otherwise lost, and that after the emptying of the sand bucket, it may be returned still without any possibility of loss of the oil. In fact, it will be observed that if the valve 50 does not fit the opening 24 in the bottom of the oil separator tightly, the leakage will be water for a considerable length of time without any escape of the oil which is floating on top of the water in the separator. Furthermore, that any gasoline that may be floating upon the water at this time will not be spilled into the sewer or permitted to escape but held in place and finally restored to the trap to be evaporated as before. Again, it is to be observed that the water running through the trap is permitted to run over the lip of the sand bucket at a considerable height above the water level standing in the trap body, so that a constant level of water is maintained up to the time when an accumulation of sand in the bucket

is sufficient to overbalance the counter-piece 46, whereupon, when the sand bucket drops, such fall results in the lowering of the oil level in the oil separator, so that when the latter is lifted out of the trap body, there is no liability of spilling oil therefrom.

This trap efficiently separates the four materials flowing into it from each other without in any way interfering with the efficiency of the operation of any one of the contrivances, thus the flow of sand through the oil separator has not the slightest effect upon its operation, because the separation of the oil and water is entirely due to the variation of levels of outlets which efficiently secures the separation irrespective of the flow of sand through the device. Furthermore, that the oil flowing out of the oil spout is entirely free from water because it has had a sufficient length of time to stand in the receptacle to gather into a continuous mass of oil, so that no water will be carried over from the oil separator into the oil bucket. Furthermore, it will be observed that wholly irrespective of what the specific gravities of the oil flowing into the trap may be, they will automatically operate to separate themselves from the water, when the specific gravity of the oil is less, by decreasing the depth of the oil, and when it is greater, by increasing the depth of the oil, the overflow level always remaining constant, but the level 29 varying with the differences in the specific gravities of the oil and the amount of gasoline lying on top of it.

While the specific embodiment of the invention is particularly adapted for use as a drain trap for automobile wash stands, it is to be understood that the invention is not limited to such use as it may be used for other purposes within the purview of the claims.

Having thus described the invention, what is claimed is:—

1. A drain trap having, in combination, a trap body, a cover or floor plate, a baffle basin located in the upper part of the trap body provided with a depending oil separator, a sand bucket located in the trap body surrounding the depending oil separator, the said baffle basin having an opening discharging into the oil separator, a counter-weight for the sand bucket, connections between the counter-weight and the sand bucket and a valve for closing the opening from the baffle basin into the oil separator connected with the sand bucket and operating upon the accumulation of sand therein to close such opening to cause the trap to overflow, substantially as described.

2. An automobile washstand drain trap for receiving gasoline and water, retaining the gasoline and discharging the water into

a sewer pipe having, in combination, a chamber in which the gasoline and water are separated by flotation, said chamber having an inlet for receiving the gasoline and water from the washstand provided with means for preventing the escape of gasoline vapor from the chamber to the washstand and an outlet for discharging the water to the sewer pipe having a liquid seal for preventing the escape of gasoline vapor into the sewer pipe, and an air inlet pipe for admitting and discharging a continuous circulation of air through said chamber and over the surface of the gasoline retained therein for vaporizing and carrying the gasoline away through the air outlet pipe, substantially as described.

3. A drain trap having, in combination, a sand bucket, an inlet for directing water mixed with sand into the sand bucket extending into the sand bucket and below the normal liquid level therein, and a valve for closing the mouth of the inlet to retain the water contained in the inlet so that it, with its contained liquid, may be removed from the sand bucket and allow the sand bucket to be emptied, substantially as described.

4. A drain trap having, in combination, a trap body, a sand bucket, an oil bucket, an oil separator located in the sand bucket, connections for directing the materials entering the trap into the oil separator, an oil connection from the oil separator to the oil bucket, and a water connection from the oil separator to the sand bucket; said oil separator operating to separate the oil and discharge it through the oil connection into the oil bucket and allow the water to flow through the water connection into the sand bucket, said sand bucket operating to catch sand and the like and allow the water to flow from the sand bucket into the trap, substantially as described.

5. A drain trap having, in combination, a trap body, a sand bucket for catching sediment passing into the trap and means for emptying the sand bucket of the accumulated sediment, an oil separator located in the sand bucket for separating oil and the like from the water passing through the trap, and connections for leading the water through the oil separator and sand bucket to the trap outlet, substantially as described.

6. A drain trap having, in combination, a trap body, a sand bucket contained therein, counterbalancing means for the sand bucket which is overbalanced by the sand bucket upon a sufficient accumulation of sand therein, a valve controlling the passage of liquid through the trap, and means connected to the sand bucket for closing the valve when the sand bucket overbalances its counterbalancing means to cause the trap to overflow, substantially as described.

65 7. A drain trap having, in combination, a

trap body, an oil separator located therein, a water chamber, a connection between the bottom of the oil separator and the water chamber, a valve for closing said connection, a water outlet for the water chamber located at the normal water line therein, an oil outlet for the oil separator located above the level of the water outlet, and means for closing the valve at the bottom of the oil separator when it is desired to remove the oil separator from the trap, substantially as described.

8. A drain trap having, in combination, a sand separator for catching sediment and the like from wash water passing into the trap and means for emptying the trap of the accumulated sediment, an oil separator for separating the oil and the like from the wash water, and connections for leading the wash water through said separators and for discharging from the trap the water from which the oil and sand have been separated, substantially as described.

9. A drain trap having, in combination, a trap body, a bucket, a counterbalance for the bucket including a counterweight which is overbalanced when the bucket exceeds a certain predetermined amount in weight, an opening for the admission of materials to the trap, a valve for closing such opening, and means connected to the counterbalance and operated thereby for closing the valve when the bucket exceeds a certain predetermined weight, so that an attempt to continue the use of the trap will cause it to overflow and indicate that attention is required, substantially as described.

10. A drain trap having, in combination, a trap body, a sand receptacle, means for supporting the sand receptacle having provision for allowing the sand receptacle to move downwardly under the influence of gravity when sufficient sand has accumulated in the sand receptacle, and means operating upon the downward movement of the sand receptacle for preventing further use of the trap until the sand receptacle is emptied, substantially as described.

11. A drain trap having, in combination, a trap body, a sand receptacle, means for supporting the sand receptacle having provision for allowing the sand receptacle to move downwardly under the influence of gravity when sufficient sand has accumulated in the sand receptacle, and means operating upon the downward movement of the sand receptacle for indicating that attention is required, substantially as described.

12. A drain trap having, in combination, a trap body, a sand bucket, an oil bucket, an oil separator, connections for directing the materials entering the trap into the oil separator, an oil connection from the oil separator to the oil bucket, and a water connection from the oil separator to the sand

bucket, said oil separator operating to separate the oil and discharge it through the oil connection into the oil bucket and allow the water to flow through the water connection 5 into the sand bucket, said sand bucket operating to catch the sand and the like, substantially as described.

13. A drain trap having, in combination, a trap body, means for separating oil and the 10 like from the water and collecting it including a removable oil bucket which can be lifted out of the trap and emptied, and means for separating sand and the like from the water and collecting it including a removable 15 sand bucket which can be lifted out of the trap and emptied, substantially as described.

14. A drain trap for washstands having, in combination, a trap body set beneath the 20 floor of the washstand with a perforated top at the floor level, means for separating oil and the like from the water and collecting it including a removable oil bucket provided with a handle which can be grasped to lift 25 the oil bucket out of the trap, and means for separating sand and the like from the water and collecting it including a removable sand

bucket having a handle which can be grasped to lift the sand bucket out of the trap, said trap body having provision for opening its 30 top for the removal of the oil and sand buckets, substantially as described.

15. An automobile washstand drain trap for receiving gasoline and water, retaining the gasoline and discharging the water into 35 a sewer pipe having, in combination, a chamber in which the gasoline and water are separated by flotation, said chamber having an inlet for receiving the gasoline and water from the washstand provided with 40 means for preventing the escape of gasoline vapor from the chamber to the washstand and an outlet for discharging the water into the sewer pipe provided with means for preventing the escape of gasoline vapor into 45 the sewer pipe, and a safety air pipe connection for the escape of the evaporated gasoline from the chamber, substantially as described.
